UNITED STATES PATENT OFFICE

ROY H. McELROY AND PAUL A. MEEHAN, OF DAYTON, OHIO, ASSIGNEES TO CAROL
ENGINEERING, INC., OF DAYTON, OHIO, A CORPORATION OF OHIO

DESIGN FOR A MULLER PAN

Application filed July 23, 1930. Serial No. 36,451. Term of patent 7 years.

To all whom it may concern:

Be it known that we, ROY H. McELROY and PAUL A. MEEHAN, citizens of the United States, residing at Dayton, in the county of Montgomery and State of Ohio, have invented a new, original, and ornamental Design for a Muller Pan, of which the following is a specification, reference being had to the accompanying drawing, forming a part thereof.

In the accompanying drawing:

Figure 1 is a side elevation of the muller pan, showing our new design;

Figure 2 is a section on the line 2—2 of Figure 1 looking in the direction of the arrows.

Figure 3 is a side elevation of the muller pan showing our new design, taken at a right angle to the view shown in Figure 1.

We claim:

The ornamental design for a muller pan, substantially as shown.

ROY H. McELROY.
PAUL A. MEEHAN.
